(57) **CLAIM**

We claim the ornamental design for a pump adapter, as shown and described in FIGS. 1-7.

DESCRIPTION

FIG. 1 is a perspective view of a pump adapter according to one embodiment of the invention.

FIG. 2 is a front view of the pump adapter shown in FIG. 1.

FIG. 3 is a rear view of the pump adapter shown in FIG. 1.

FIG. 4 is a top view of the pump adapter shown in FIG. 1.

FIG. 5 is a bottom view of the pump adapter shown in FIG. 1.

FIG. 6 is a first side view of the pump adapter shown in FIG. 1; and,

FIG. 7 is an opposite side view of the pump adapter shown in FIG. 1.

The broken line showing of the environment is for illustrative purposes only and forms no part of the claimed design.
